UNITED STATES PATENT OFFICE.

LEO OPPENHEIM, OF NEW YORK, N. Y.

PAPER-FASTENER.

1,250,343.

Specification of Letters Patent. Patented Dec. 18, 1917.

Application filed August 10, 1916. Serial No. 114,145.

To all whom it may concern:

Be it known that I, LEO OPPENHEIM, a citizen of the United States, residing at New York, in the county of New York and State 5 of New York, have invented certain new and useful Improvements in Paper-Fasteners, of which the following is a full, clear, and exact specification.

This invention relates to paper fasteners 10 composed of two wings having penetrating devices which when compressed set and lock sheets of paper together. These fasteners, as heretofore made have been U-shaped, and the wings have been flat in transverse section. When compressed the wings bend, and upon release of the compression tend to 15 spring apart slightly owing to the resilience of the metal and, owing to the U-bend do not set sufficiently close and do not tightly 20 hold the sheets of paper.

An object of this invention is to confine the set which is required in such a fastener to the bend itself, and this is accomplished by making the wings substantially non- 25 resilient, so that when compressed, all of the yielding is localized at the bend, instead of being partly at the bend and partly in the wing, as in prior devices. I accomplish this by stiffening the wings longitudinally from 30 adjacent the bend to adjacent the outer ends. By my invention, as specifically shown herein, the wings are stiffened by corrugations in the shape of letters or designs struck up 35 on them to form ridges and grooves and the edge of portions of the wings are beaded. This stiffening prevents the wings from bending when the fastener is being set and confines the flexure to the curved portion between them so that the wings do not spring 40 back upon release of the setting pressure but remain in close engagement with the paper between them. The stiffness of the wings permits the fastener to be made of thinner stock and any desired curvature may be 45 given to the connecting neck and the curve there, may be so short as to approach substantially to a V-shape bend. These stiffening means serve also as finger holds in grasping the fastener and attractively ornamenting 50 the wings with distinctive marking.

The fastener of this invention has its wings provided with mating prongs and prong housings or sockets to pierce and grip

the paper. Heretofore it has been the practice to form these housings or sockets as substantially circular recesses which in the closed position of the fastener surround the points of the prongs. Such sockets particularly with tough paper often allow the prongs to force the paper up into the prong 55 housing (the open or closed kind) without piercing it, and do not hold the papers in proper manner to be penetrated by the prongs. On release of the setting pressure the paper pushed into the socket tends to 60 spread the wings apart and loosen the fastener. In this invention these defects are overcome by providing the sockets with lower cutting edges which lie in close proximity to the prongs and coöperate with them 65 to pierce the paper. By these cutting edges the papers are held rigid against the piercing prongs which penetrate them easily and completely and the prong points are housed within the sockets so that the fastener is 70 positively locked on the paper. 75

In socket housing designs heretofore in use, the piercing prongs, particularly when fastening a few sheets of paper, protrude through the upper wing and often prick the 80 fingers of the operator. As these fasteners are usually of brass such accidents may be particularly serious. In order to protect the fingers of the operator the sockets or housings of this invention are deepened by inwardly directed toothed flanges or prongs 85 and by the struck up stiffening ridges arranged to surround the socket housing or so that the prongs are entirely sheathed. These toothed flanges or prongs protrude within 90 the inner face of the wing 1 and are advantageous in that they serve to grip the upper papers more securely and hold the papers against the piercing prongs. There is thus formed a fastener which may be safely 95 pressed to a sure hold on the paper.

The fastener is formed wide lengthwise of the connecting neck or hinge, and comparatively short along a normal to the hinge. The gripping prongs carried by the 100 wings can therefore be well separated to give a wide grip on the paper so that the papers will not swivel on the gripping means and become disarranged. This broader construction and binding is at- 105 tained with substantially no increase in the

area of metal employed. The fastener is therefore cheap in construction and most efficient in its action.

In the accompanying drawings,

5 Figure 1 is a perspective view of the fastener when ready for use;

Fig. 2 is a plan view of the inner faces of the fastener before bending; and

10 Fig. 3 is a section view on the line 3—3 of Fig. 1 showing the fastener closed on the paper.

15 In the drawings, 1 and 2 are the fastener wings connected by the curved neck portion 3. The wing 1 is provided with the struck up curved ridges 4, 5 and 6 with interconnecting loops serving as stiffening means for said wing to hold it against bending when the wings are pressed together. These 20 stiffening ridges due to the placing of the looped ridges 4, 5 and 6 form the letter E extending from the curved neck between the wings to the outer edge of the wing 1. These looped ridges together with the bead 7 at the outer edge of the wing 1 serve to 25 hold said wing stiff against flexure when the fastener is being pressed closed on the papers.

30 The other wing 2 is also provided with stiffening means and in the embodiment shown this is accomplished by striking up the word Eclipse in elongated letters extending from the bend 3 to the end of the wing. The wing is also provided with an edge bead 8. The lettering and beading together 35 hold the wing stiff when pressed to grip the work. The stiffening of both the wings therefore confines the entire flexure to the connecting curved neck 3 so that where there is such a concentrated deformation 40 of the metal it is bent far beyond the elastic limit and upon release of the setting pressure the fastener wings remain in close engagement with the paper between them.

45 To grip the paper between the wings, mating-prongs and socket housings are provided which pierce the papers. The sockets or housings 10, 11 and 12 are carried by the wing 1 within the looped ridges 4, 6 and 5, respectively, while the piercing prongs 13, 50 14 and 15 are struck up from the other wing 2 in position to enter the socket housings 10, 11 and 12 respectively. In order to hold the paper snugly and flatly down against the prongs during the closing operation, the 55 sockets are provided with cutting edges 16 which in the closed position of the fastener lie close to the prongs. During the piercing of the paper these edges coöperate with the prongs to effect a complete and neat penetration and in effect form with the prongs mating cutting edges. To further grip the paper and to hold it down against the prongs, the socket housings are also provided with segmental flanges 17 or prongs 60 65 between the wings and protruding within

the inner face of the wing 1. These flanges 17 together with the edges 16 and the looped ridges around the sockets serve to deepen the sockets to such an extent that in no position will the prongs protrude through sufficiently to prick or lacerate the fingers of the operator.

70 The fastener is preferably so formed that its dimensions lengthwise of the connecting neck 3 are greater than the length of the wings from the neck. In this way the grip is greater and besides positioned near the edge of the paper. The prongs can be spaced relatively far apart to give a wide and greater grip, which will effectually prevent any swiveling or pivoting of the papers. The localizing of the flexure at the bend makes the connecting neck act like a hinge holding the stiffened wings exactly 80 opposite each other and accurately registering the prongs and prong housings no matter how the wings are pressed together.

85 The stiffening means on the wings provide convenient finger grips. In the embodiment shown, the sockets of the wing 1 90 are so disposed as to leave the central outer portion of the wing free for finger pressure. With the fastener constructed as described there is little or no recoil from full closed position. The flexure is restricted 95 to the curved neck 3 and the papers are held tightly down on the piercing prongs and the penetration is complete so that the paper will not spread the wings when released. By my improvements the setting of the fastener on any thickness of paper is made safe 100 and its grip secure.

105 It is evident that the form and proportions of the fastener may be varied from those specifically disclosed and that any desired means may be used to stiffen one or both of the wings. The invention is not confined to the specific embodiment shown, but is intended to cover such modifications thereof as fall within the scope of the appended claims.

110 Having thus described my invention, I declare that what I claim as new and desire to secure by Letters Patent, is:—

115 1. A paper fastener comprising opposite holding portions connected by a bent portion, a prong on one of said portions, and a housing on the other of said portions having a coöperating cutting edge in close proximity to the point of said prong when fastened on the paper.

120 2. A paper fastener comprising opposite holding portions connected by a bent portion, a penetrating prong on one holding portion, and a substantially semi-circular housing on the other holding portion having its straight edge parallel to the plane of said prong and coöperating with said prong to cut the paper.

125 3. A paper fastener comprising opposite

holding portions connected by a bent portion, a penetrating prong on one holding portion and a mating housing on the other holding portion having an inwardly directed 5 flanged edge, and a substantially straight cutting edge.

4. A paper fastener formed by bending a single piece of sheet metal and comprising opposite holding portions connected by a 10 resilient curved neck adapted to bend throughout its length to grip the paper between said holding portions when pressed together, paper penetrating means comprising a prong on one holding portion and a 15 mating socket on the other holding portion having an edge surrounding and housing said prong in set position and coöperating therewith to cut the paper, and longitudinal stiffening means formed by bending one of 20 said holding portions and extending from said neck to the point of application of the setting pressure to confine the bending flexure to the metal of said neck so that the holding portions will remain in close engagement 25 with the paper and said prong and socket will swivel about said neck and be brought into accurate register when set.

5. A paper fastener formed by bending a

single piece of sheet metal and comprising opposite holding portions at an angle to each other and adapted to be pressed together to grip the paper between them, paper penetrating means comprising a plurality of prongs and mating sockets on said holding portions, said sockets having edges surrounding and housing said prongs in set position and coöperating therewith to penetrate the paper at widely separated points, a curved connecting neck between said holding portions adapted to bend throughout its 40 length and wider than the distance from said neck to said prongs, and longitudinal stiffening means formed by bending one of said holding portions and comprising struck up ridges looped around said sockets to increase their depth and extending from said neck to the point of application of the setting pressure to confine the bending flexure to the metal of said neck so that the holding portions will remain in close engagement 45 with the paper and said prongs and sockets will swivel about said neck and be brought into accurate register when set.

In testimony whereof I affix my signature, in presence of two witnesses.

LEO OPPENHEIM.
